CLAIM

The ornamental design for an electrical safety plug, as shown and described.

DESCRIPTION

FIG. 1 is an environmental perspective view of an electrical safety plug showing my new design;

FIG. 2 is a front elevational view thereof;

FIG. 3 is a rear elevational view thereof;

FIG. 4 is a top view with the bottom being a mirror image thereof;

FIG. 5 is a right side elevational view with the left side being a mirror image thereof;

FIG. 6 is a front elevational view of a second embodiment of an electrical safety plug showing my new design;

FIG. 7 is a rear elevational view thereof;

FIG. 8 is a top view with the bottom being a mirror image thereof; and,

FIG. 9 is a right side elevational view with the left side being a mirror image thereof.

The broken line showing of a plug, a mating electrical safety receptacle, and a plate is for illustrative purposes only and forms no part of the claimed design.
